DESIGN FOR A SOAP CAKE OR SIMILAR ARTICLE

Herbert S. Scott, New Canaan, Conn., assignor to Parfums Schiaparelli, Inc., New York, N. Y., a corporation of New York

Application December 6, 1943, Serial No. 111,923

Term of patent 14 years

To all whom it may concern:

Be it known that I, Herbert S. Scott, a citizen of the United States and a resident of New Canaan, Fairfield county, State of Connecticut, have invented a new, original, and ornamental Design for a Soap Cake or Similar Article, of which the following is a specification, reference being had to the accompanying drawing, forming a part thereof, in which:

Fig. 1 is a top plan view of a soap cake, showing my new design;

Fig. 2 is a side elevational view;
Fig. 3 is an end elevational view thereof; and
Fig. 4 is a sectional view taken on the line 4—4 of Fig. 3.

I claim:

The ornamental design for a soap cake or similar article, as shown.

HERBERT S. SCOTT.
